UNITED STATES PATENT OFFICE.

JOHN J. RECTENWALD, OF LOGAN, OHIO.

RUNNING-BOARD SADDLE.

1,269,306.

Specification of Letters Patent.

Patented June 11, 1918.

Application filed October 26, 1915. Serial No. 58,071.

To all whom it may concern:

Be it known that I, JOHN J. RECTENWALD, a citizen of the United States, residing at Logan, in the county of Hocking and State 5 of Ohio, have invented certain new and useful Improvements in Running-Board Saddles, of which the following is a specification.

My invention relates to new and useful 10 improvements in an attachment for box cars, and more particularly to a running board saddle.

The primary object of the invention is the provision of a device of this character 15 whereby the running board may be easily secured to the roof of the car.

A further object of the invention is the provision of means whereby there will be no danger of a leak through the car roof 20 through which the bolt passes for connecting the saddle to the roof.

With these and other objects in view, the invention consists in the novel details of construction and arrangement of parts which 25 will be more clearly understood from the following description and drawings, in which:

Figure 1 is a side view of the saddle showing a transverse section through the running 30 board,

Fig. 2 is a top plan view of the saddle,

Fig. 3 is a longitudinal section on the line 3—3 of Fig. 2, looking in the direction of the arrow,

Fig. 4 is a longitudinal cross section on the line 4—4 of Fig. 3, looking in the direction of the arrow,

Fig. 5 is a end view of the saddle, and

Fig. 6 is a transverse section on the line 40 6—6 of Fig. 4.

In the drawings the numeral 1 indicates the web of the saddle, the lower edge of which is inclined from the ends toward the center, as is clearly shown in Figs. 1 and 3 45 of the drawings. The lower edge is shaped in this manner to conform to the curvature of the roof of the car. The lower edge of the web 1 is bifurcated or split longitudinally, as is clearly shown in Figs. 3, 5 and 50 6 of the drawings, thereby forming the supporting flanges 2, which engage the roof of the car. A transverse opening 3 is formed in the web 1, extending through the supporting flanges 2 and terminate in an elongated recess 4 which terminates a short distance above the top of the web. Recesses 5

are formed on opposite sides of the elongated openings 4 and opposite ends thereof, thereby forming shoulders, the purpose of which will be presently described. A recess is also 60 formed at the inner ends of the recesses 5. A flange 6 is formed on each side of the top of the web 1 and said flanges are provided with enlarged portions indicated at 7, each of which has a notch formed therein, as is 65 clearly shown in Fig. 2 of the drawings. The notches are indicated at 8 and terminate a short distance from the web 1, as is clearly shown in Fig. 5 of the drawings. The running-board is provided with a plurality of 70 sections indicated at 9 which are adapted to be received upon the top of the saddle, as is clearly indicated in Fig. 1 of the drawings. The sections are secured to the saddle by means of bolts 10, which pass through the 75 sections and are received in the notches 8 in the enlargement 7 of the flanges on the top of the saddle. Nuts 11 are received on the ends of the bolts and hold them in position.

The saddle is adapted to be secured to the car roof, by means of a central bolt, which is indicated at 12, said bolt having an enlarged elongated head 13, which is adapted to pass through the elongated opening 4 formed in 85 the web 1. After the head of the bolt has been passed through the elongated opening 4, the bolt is given a quarter turn, thereby bringing the head against the shoulders formed by the recesses 5, as is clearly shown 90 in Fig. 4 of the drawings. The head then drops into the recesses at the inner ends of the recesses 5. It will be understood that after the bolt is secured to the saddle, it passes through the roof of the car, and is 95 secured in position by means of a nut received on the threaded end of the bolt.

Depressions 14 are formed on each side of the web 1, thereby lightening the weight of the saddle. While I have described only 100 one saddle, it will be understood that it is necessary to use a plurality of saddles on the top of the car, thereby supporting the running-board in a proper manner. The number of saddles used, will depend considerably 105 upon the length of the car.

Having fully described the detailed construction of my invention it is thought that the many advantages will be understood. In the past considerable difficulty and inconvenience has been caused when the running-board has been nailed or otherwise secured 110

directly to the roof of the car. The opening caused by the fastening means passing through the roof would allow water to pass through the openings, thereby damaging the contents of the car. By using my improved saddle it is impossible for any moisture to leak through the roof of the car and the contents thereof are thereby kept in a dry condition. It will be noted that only one bolt passes through the roof for each saddle, and there is no direct opening through which moisture could pass. The head of the bolt is received in the recess beneath the top of the saddle and there is no way in which liquid could pass through the bolt-opening. In assembling my device, the saddle is placed upon the roof of the car, the bolt 12 having been previously placed in position, as shown in Figs. 3, 4 and 6 of the drawings. After the bolt is passed through the roof of the car, the nut is placed in position upon the threaded end of the bolt and the saddle will thereby be held in secured position against either longitudinal or lateral movement. The sections of the running-board are then placed upon the saddle and the bolt 10 passed therethrough and into the notches formed in the flanges on the sides of the saddle. After the bolts are placed in the notches in the desired position, the nuts 11 are placed upon the threaded end of the bolts and tightened into position.

By bifurcating or splitting the lower edge of the web longitudinally, it will be seen that any moisture which might enter the transverse opening 3 can flow therefrom over the sides of the car. In this manner, there is no danger whatever of the water passing through the openings formed by the bolts.

Having fully described my invention what I claim as new and desire to secure by Letters Patent is:

1. A running board saddle comprising a web having an elongated opening extending from the bottom and terminating a distance from the top, recesses formed on each side of the elongated opening and of greater depth at one end than the other, and a bolt, said bolt having an elongated head adapted to pass through the elongated opening and to be received in the deepest portion of the recesses.

2. A running board saddle comprising a web having an elongated opening extending from the bottom and terminating a distance from the top, recesses formed on each side of

the elongated opening at opposite ends thereby forming shoulders, and a bolt, said bolt having an elongated head adapted to be passed through the elongated opening and be received between the shoulders.

3. A running board saddle comprising a web having an elongated opening extending from the bottom and terminating a distance from the top, recesses formed on each side of the elongated opening at opposite ends thereby forming shoulders, said recesses being of greater depth at the ends adjacent the shoulders, and a bolt, said bolt having an elongated head adapted to be passed through the elongated opening and to be received in the deepest portion of the recesses and between the shoulders.

4. A running board saddle comprising a web, and flanges formed on each side of the top of the web, said flanges having notches formed therein.

5. A running board saddle comprising a web, the lower edge of which is bifurcated longitudinally and provided with an elongated opening extending from the bottom and terminating a short distance from the top, recesses formed on each side of the elongated opening, a bolt having an enlarged head adapted to be received in the elongated openings and recesses, flanges formed on each side of the top of the web, running boards adapted to be received upon the saddle, and means passing through the running boards and flanges for securing them in position.

6. A running board saddle comprising a web, the lower edge of which is bifurcated longitudinally and provided with an elongated opening extending from the bottom and terminating a distance from the top, recesses formed on each side of the elongated opening, near the top thereof, a bolt having an enlarged head adapted to be received within the elongated opening and recesses, flanges formed on the top of the web, enlargements formed on the flanges and provided with notches, running boards adapted to be received upon the saddle, and bolts adapted to pass through the running boards and be received within the notches of the enlargements.

In testimony whereof I affix my signature in presence of two witnesses,

JOHN J. RECTENWALD.
